TANK CONSTRUCTION

Harry H. Hendon and Howard A. Van Orman,
Birmingham, Ala., assignors to Knock Down
Tanks Inc., a corporation of Alabama

Application September 28, 1949, Serial No. 118,228

1 Claim. (Cl. 220—5)

1

This invention relates to metal septic tank for the disposal of sewage, and is of the general type described in our pending application Serial Number 85,912, filed April 6, 1949, now Patent No. 2,553,885, dated May 22, 1951.

The principal object of our invention is to provide a septic tank which shall be constructed in sections capable of being nested together to occupy a relatively small space in storage and shipping, and which may be readily assembled and installed.

Another object is to provide a sectional septic tank wherein the sections are adapted to be nested and occupy little space in storage and shipping and which shall include a simple, fluid tight joint between the sections.

A further object is to provide a sectional septic tank which may include at least one removable baffle and in which the sections may be nested together for shipping with the baffle removed from its operating position, together with means to hold the sections and baffle against shifting during shipment, and to hold the baffle in position after assembly.

A still further object is to provide a sectional septic tank which shall have an integral top on the upper section, the top being provided with a clean out opening having a fluid tight cover therefor.

A further object is to provide a sectional metal septic tank the upper section of which shall be so constructed as to provide the maximum of strength with a minimum of weight.

A still further object is to provide a sectional metal septic tank of maximum strength and relatively light weight and which shall meet modern requirements set by health authorities for residential septic tanks.

As is well known in the art to which our invention relates, assembled metal septic tanks are bulky to handle and are of low weight relative to size. These characteristics present difficulties in the manufacture and in the storage and shipping thereof and subject them to a relatively high freight rate. We have found by making such tanks in sections with the sections adapted to nest together, that appreciable economies in manufacture, storage and handling are obtained. Also, due to the lower freight rate thus obtained, material savings in freight cost are realized. In order to adapt the sections for nesting, we make the upper section of the tank slightly smaller in its dimensions than the lower section so that the upper section may be inverted and nested into the lower section.

The upper section has sides which converge upwardly slightly when in the operating position. The sides of the upper portion are turned inwardly near the top at approximately a 45° angle to join a horizontal top. The upper section is provided with an outturned flange at its lower edge which is adapted to engage within

2

an outwardly and upwardly turned stiffening flange along the upper edge of the lower section, thereby giving added strength to the tank. The flanges may be joined together by bolts to retain the sections in either the nested position or in the operating position. The flanges, when the sections are in the operating position, form a groove around the tank which is filled with a bituminous or other suitable sealing material thus providing a fluid tight joint. A bituminous coating may be applied to both sections by hot dipping. The cover for the clean out opening is in place when the top section is dipped and is thereby sealed in place. This makes the erected tank fluid tight with the exception of the inlet and outlet connections.

A septic tank embodying features of our invention is illustrated in the accompanying drawing, forming a part of this application, in which:

20 Fig. 1 is a perspective view of an erected septic tank;

Fig. 2 is a longitudinal sectional view of an erected septic tank;

Fig. 3 is a transverse sectional view taken 25 along line III—III of Fig. 2;

Fig. 4 is a transverse sectional view of a septic tank in the nested position; and,

Figs. 5 to 8 inclusive are detail sectional views showing various forms of joints which we may employ between the sections.

Referring now to the drawings for a better understanding of our invention, we show in Fig. 1 a rectangular septic tank comprising a lower section 10 and an upper section 11. The lower section 10 is provided with a bottom 12, sides 13 and ends 14. The upper section 11 is provided with ends 16, an integral top 17 having a man-hole or clean out opening 18 therein and sides 21. A cover 18' for the manhole is manually held 40 in place by clips 19. The upper section is slightly shorter, slightly narrower, and slightly shallower than the lower section to provide for inverting and nesting the sections. The sides 21 of the upper section also converge inwardly toward the top to further aid in nesting. Near 45 the top they are both turned inwardly at a 45° angle as shown at 15 and 15' to join the horizontal portion of the top 17. The horizontal top of the tank is from $\frac{1}{2}$ to $\frac{3}{4}$ the width of the tank at the point where the top portions of the 50 side walls turn inwardly. This forms a truss, or arch shaped top portion which provides greater resistance to the earth load on top of the tank when in use and also reduces the unsupported span at both the sides and the top.

55 The lower section 10 of the tank is provided with an outwardly and upwardly turned flange 22 along its upper edge extending all around the section. The upper section 11 is provided with an outwardly turned flange 23 extending all 60 around the section along its lower edge, which

is adapted to fit within the flange 22. The flanges may be joined together by bolts 24 to retain the sections in either the nested position, as shown in Fig. 4, or in the operating position as shown in Fig. 3. The flanges 22 and 23 give added strength to the tank and increased resistance to pressure due to packing earth around the tank when it is installed and to water pressure from within. We are thus enabled to provide a tank of the requisite strength with a minimum thickness of material and without additional reinforcing members.

The outwardly turned flange 23 on the upper section when in operating position, provides a sealing groove 26 as shown in Fig. 5 which extends all around the tank. This groove is filled with a suitable sealing material 27, for example, a bituminous material such as asphalt, or tar, to provide a fluid tight joint. Another form of joint is shown in Figs. 7 and 8 in which the bituminous material 27' is wiped into the flange 22' in a triangular shape in cross section. The upper section of the tank is then set into position on the lower section and the flange 23' compresses the bituminous material between the two flanges of the joint on the side where it is subject to internal pressure. The flange 23' on the upper section is slightly downwardly inclined with respect to the horizontal as shown, and the flange 22' on the lower section is slightly upwardly inclined with respect to the horizontal as shown in Figs. 7 and 8. The shape of the joint thus formed leaves a wedge shaped ring 25 of the compound on the inside of the joint which makes it permanently fluid tight. After the bolts 24' have been tightened the groove 26' above the flange 23' may be also filled with the sealing material 27' to further seal the tank and protect the bolts.

When the tank is constructed a bituminous coating may be applied to both sections thereof by hot dipping. Each half is submerged in a suitable heated vat of coating material. The open construction provides ready drainage of the excess coating material as the sections are removed from the dipping vat. When the top section of the tank is dipped in the coating compound the cover 18' for the clean out opening is thus sealed in place, and except for the inlet and outlet connections the erected tank is fluid tight. The upper section 11 of the tank is provided with the usual inlet opening 28, at one end and an outlet opening 29 at the opposite end. The inlet connection 28 and outlet connection 29 are made flush with the outside of the tank so as not to interfere with the nesting of the sections. Inwardly of the opening 28 is an inlet baffle 31 and inwardly of the opening 29 is an outlet baffle 32, both being typical in construction and are welded into the top section of the tank.

Sectionalizing baffles 33a and 33b may be provided across the tank by welding the upper baffle 33a in place in the upper section of the tank and fastening the lower baffle 33b to the lower section of the tank by means of a metal hinge or clip 34. When the tank is in the nested position as shown in Fig. 4, the lower baffle 33b is lying on the tank bottom. When the tank is erected the lower baffle 33b is raised to a vertical position and is held in that position by metal clips 36 which have one end welded to the walls of the lower section 10. The upper and lower baffles are spaced apart sufficiently, as shown, to permit the passage of liquid thereby. Also, the lower baffle 33b may have a portion removed at the bottom, such as shown at 35 to provide drainage thereby.

Sewage is introduced into the upper section 11 of the tank through the inlet connection 28 and is directed downwardly by the inlet baffle 31. Liquid flows out under the outlet baffle 32 and outlet 5 29 to the soil disposal area, as is well understood.

As shown in Fig. 4 of the drawings, section 11 is inverted from the position shown in Fig. 3 when nesting the sections for storage and shipping and is inserted within the section 10. The dimensions 10 of section 11 are sufficiently less than those of section 10 so that it fits readily within section 10.

From the foregoing, it will be apparent that we have devised an improved tank construction 15 which is simple of design, economical of manufacture, having the maximum of strength, with a minimum of weight and one which may be packaged for handling and shipping so as to occupy relatively small spaces in storage and shipping, thereby greatly reducing cost of 20 handling and the freight rates applicable to its shipment.

Throughout this specification we have described the upper section of our improved tank 25 as being smaller than, and nesting within, the lower section. We wish it understood however that this is for convenience of description only, as it may be constructed for the lower section to be nested within the upper.

While we have shown our invention in but one 30 form, it will be obvious to those skilled in the art that it is not so limited, but is susceptible of various changes and modifications, without departing from the spirit thereof, and we desire, therefore, that only such limitations shall be placed 35 thereupon as are specifically set forth in the appended claim.

What we claim is:

A rectangular metal septic tank comprising a lower section, an upper section having an inlet 40 and an outlet and having slightly smaller dimensions than the lower section whereby when inverted it is adapted to nest within the lower section, a reinforcing flange extending around the upper edge of the lower section inclined slightly 45 upwardly from the horizontal and terminating in a vertically extending portion, and a reinforcing flange extending around the lower edge of the upper section inclined slightly downwardly from the horizontal and engaging the upper surface of 50 the slightly upwardly inclined flange on the lower section and forming a wedge shaped groove extending around inside of the joint and a groove extending around the outside of the joint, and bituminous sealing material in said grooves.
